MACHINE FOR MAKING SHEET-METAL-PIPE ELBOWS.

Application filed March 28, 1925. Serial No. 19,011.

My invention relates to the art of making elbows out of sections of sheet metal pipe by forming transverse crimps or folds in that side of the pipe which constitutes the inside 5 or shorter curve of the elbow when completed. The invention is particularly useful for operation on pipe of relatively brittle metal, such as zinc, which has heretofore not been extensively used for elbows notwithstanding its superiority therefor by reason of its resistance to corrosion, because of its tendency to crack when sharply bent as in the machines heretofore in use. In my improved machine and process, the folds of the 10 crimp are not crushed flat in the initial operation of the machine thereon as in prior machines, but are first formed with slightly rounded bends and thereafter flattened completely by a partially drawing or smoothing 15 operation as will be understood from the following detailed description, thus avoiding the severe strains on the sheet metal of the tubes which are apt to crack them at the bend, especially when the tubes are of a less 20 ductile metal, such as zinc. In my improved machine and process moreover it is possible and in fact desirable to operate on pipe sections, the seams of which are previously completely locked so that there is substantially 25 no relative movement between the interlocking edges. Thus, no further operation upon the elbows is necessary after they are formed in the machine, as required in the case of the product of prior art machines. 30 Furthermore, in the preferred form of the machine, the pipe is crimped on the portion of its periphery opposite the seam, the crimps diminishing and finally fading out at a short distance on the respectively opposite 35 sides of the seam, so that the seam stiffens the pipe along the exposed outer side of the elbow where stiffening is particularly desirable. Other features and advantages of 40 my invention will appear from the following detailed description of the preferred form thereof. It is to be understood, however, that the specific disclosure is for the purpose of exemplification only and that the definition of the scope of the invention is 45 reserved for the following claims in which I have endeavored to cover it as broadly as the prior art permits.

In the drawings accompanying and forming a part of the application, Figure 1 is a 50 side elevation of a machine embodying my

invention in its preferred form, the machine being shown as partly broken away to show features of the construction which would otherwise be hidden; Fig. 2 a plan view of the same; Fig. 3 a vertical section on an enlarged scale of the forward end of the machine; Fig. 4 a similar view of the rear end of the machine and an elevation of certain elements of the front portion of the machine, intermediate parts being broken away; Fig. 5 a transverse vertical section on the plane of the line 5—5 of Fig. 3; Fig. 6 a horizontal section partly in elevation; Fig. 7 a rear end view of a detail, parts being omitted for the sake of clearness; Fig. 8 a transverse vertical section on the plane of the line 8—8 of Fig. 9; Fig. 9 a longitudinal section of a portion of the machine on the planes of the line 9—9 of Fig. 8; Fig. 10 a plan view partly in section of a detail; Fig. 11 a transverse vertical section on the plane 11—11 of Fig. 3, parts being shown in elevation; Fig. 12 a similar view partly broken away and with the parts in a different position which they occupy during the operation of the machine; Fig. 13 a front end view of the machine partly broken away to better show the construction; Fig. 14 a transverse vertical section on the plane of the line 14—14 of Fig. 3; Fig. 15 a longitudinal section on an enlarged scale of a portion of the machine showing the parts in a position which they occupy during the making of a crimp; Fig. 16 a similar view showing the parts however in a different position; and Fig. 17 an elevation of a completed elbow.

I have shown my machine as designed for the making of elbows from corrugated sections of pipe of the form now in common use for rain water conduits but, as will be manifest from the following detailed description, with obvious changes it may be used for making elbows of pipe of other cross sectional form, such as cylindrical pipe. It has in common with earlier machines for the same purpose a fixed mandrel over the end of which the section of pipe from which the elbow is to be formed is fed step by step, a swinging mandrel or interior die, an expander operable between the fixed and swinging mandrels for forming the transverse bulges in the pipe which ultimately constitute the flattened crimps thereof, a clamp or gripping means surrounding the

fixed mandrel and adapted to grip the pipe sufficiently during the crimp forming operation and to cooperate in the latter, but to permit the pipe to be pushed therethrough intermediate the crimping operations and a clamp cooperating with the swinging mandrel to flatten and complete the crimp and properly hold the pipe against the swinging mandrel during the formation of the following crimp.

The fixed mandrel is of a length to receive the pipe lengths to be formed into elbows and is formed in two sections, the rear section 30 being supported at its rear end as at 31 in a bracket 32 on the frame or stand 33 of the machine, see Fig. 3. The forward section 34 of the mandrel is threaded on the reduced forward end 35 of the rear section. Exteriorly the mandrel is formed throughout its operative length in accordance with the cross-sectional shape of the elbow to be formed; in the present example of the invention I have shown the mandrel as corrugated as this machine is designed for the manufacture of elbows from corrugated pipe, such as shown in Fig. 17. The forward or end section 34 of the mandrel houses and guides the expanders for forming the bulges in the pipe, and these expanders are operated by a plunger 36 extending through and reciprocable in the mandrel as will presently appear.

Referring now more particularly to Figs. 3, 8 and 7, it will be seen that the expanders for bulging or expanding the metal of the tube to form the crimps of the elbow, comprises a series of knuckles 38 which are arranged just beyond the end edge of the fixed mandrel and are so mounted as to be capable of swinging in and out in planes radial to the mandrel. The knuckles are formed on the ends of arms or bars 39 which have a limited longitudinal and swinging movement in radial slots or recesses 40, formed in the end of the mandrel. The longitudinal movement of the knuckle bars is limited by the engagement of toes 41 on the respective bars in slots 42 in the wall of the mandrel. The inner edges of the rear portions of the knuckle bars are curved to rock upon a ring 43 which is sleeved upon the plunger 36 after the bars 39 have been inserted into their positions with their toes in the slots as above described. The knuckles are swung in and out the required distance to form the bulge and retreat within the circumference of the mandrel by links 44, the inner ends of which are reciprocated or swung longitudinally of the mandrel by the plunger 36.

In the preferred construction shown, the end of the plunger is reduced as at 45 to receive a collar 46 which is rabbeted or cut away for a portion of its periphery, corresponding in location to the knuckles, as at

47. The cut-away portion of the collar 46 is occupied by sector-shaped blocks 48 to which the respective links 44 are pivoted as at 49, see Figs. 8 and 9. The sector-shaped blocks are respectively formed or provided with pins 50 which extend into holes suitably located in the collar 46 to receive them and the end of the reduced portion of the plunger is threaded as at 52 to receive a nut 53. After the sector blocks have been put in place the nut is screwed on the end of the plunger and holds them in position. Obviously with the construction just described, when the plunger 36 is reciprocated the bulge forming knuckles are alternately spread to the position shown in Fig. 9 and retracted to the position shown in Fig. 3. The means for reciprocating the plunger will be presently described.

As will be readily understood from Fig. 8, the expanding or bulge-forming knuckles are distributed about so much of the circumference in which the crimp is to be formed in the pipe section, there being, however, a substantial arc in which no such knuckles are provided. This arc corresponds to the outside portion α of the elbow, see Fig. 17, that is to say, the portion of maximum radius, in which also the seam of the pipe is located, so that the latter does not interfere in any way with the formation of the crimp. In the construction shown the crimping mechanism is so arranged that the pipe lengths may be inserted with their seams underneath. Obviously the knuckles are shaped according to the cross-sectional shape of the pipe section. In the machine illustrated which is adapted for the making of elbows from corrugated pipe, not only the mandrel is corrugated, as before explained, but the knuckles are so formed as to extend into and engage the internal concavities or channels of the pipe without unduly distorting them except to form the transverse bulge.

A swinging mandrel or head 54 of substantially the diameter of the main or stationary mandrel and concentric therewith is hinged to the latter as best shown in Fig. 9, so as to normally form a continuation of the stationary mandrel beyond the plane of the bulge-forming knuckles. In the particular machine chosen for illustration of the invention a bore 56 is formed in the metal 57 of the end of the stationary mandrel and a similar bore 58 in the metal of the swinging mandrel, the two bores being in line. Plugs 59, 60 are inserted in the respective bores and pivoted or knuckled together at 61. Screws 62, 63 hold the plugs in their respective sockets.

It will be noted that the adjacent ends of the fixed and swinging mandrels respectively are inclined so that when they are in normal coaxial positions as shown in Fig. 9 the space between said mandrels corresponds in gen-

eral form and dimensions with the bulge to be formed in the pipe sections and provides room for the expanding knuckles to operate between the adjacent edges of the respective mandrels. The bulge which is to form the crimp in the pipe is formed by spreading or expanding the knuckles when the fixed and swinging mandrels are coaxial as shown in Fig. 9. After the bulge has been formed and the expanding knuckles retracted, the swinging mandrel is swung over until its edge is close to that of the fixed mandrel and substantially parallel thereto to fold or flatten the bulge into a crimp as will be presently explained.

During each crimp-forming operation the pipe section is firmly clamped to the respective mandrels. For this purpose, I provide what I shall term a fixed clamp, inasmuch as it has no bodily movement, in connection with the fixed mandrel and a swinging clamp pivoted coaxially and movable with the swinging mandrel. Both of these clamps are supported from a transverse web or bracket mounted upon the frame of the machine and formed with an opening 68 through which the fixed mandrel projects. The construction and operation of the fixed clamp may best be explained in connection with Figs. 3, 11 and 12. Swinging jaws 66, 67 are pivoted to the web 65 immediately above and on opposite sides of the center of the opening 68. By reference to Fig. 3, it will be seen that the opening 68 is of slightly larger diameter than the exterior of the mandrel to permit a pipe section on the latter to extend therethrough, and that the opening flares to the rear. The bearing faces 69, 70 of the respective jaws conform to the shape of the mandrel and of the pipe section on which the machine is designed to operate and are nearly semi-circumferential, meeting together in a diametric plane below the mandrel. They are formed at their free ends with lugs 71, 72, respectively, the outer or remote edges 73, 74 of which are approximately parallel to their meeting edges. The lower edges 75, 76 of the lugs are chamfered or inclined for a purpose which will presently appear. A locking slide plate 77 slides in vertical guides 78, 79 secured to the face of the web 65, the upper face of the slide plate being provided with a notch 80 of a width slightly greater than the combined width of the lugs 71, 72 when the clamp is closed. The slide plate is adapted and designed to be raised to the position shown in Fig. 11, in which the lugs enter the notch and the clamping jaws are firmly locked in closed position. On opposite sides of the notch the upper edge of the slide plate inclines upwardly in opposite directions, thus making a flaring throat. As the jaws are spread when the slide plate is lowered, when it is moved upwardly the cammed up-

per edge of the slide plate forces the lugs toward the central position and into the locking notch. A wire spring 81 is interposed between the lugs on the respective clamp jaws, the ends of the spring entering sockets 70 therein, so that the spring yieldably forces the jaws into the open position shown in Fig. 12 when the locking slide plate is in lower position. But when the slide plate is raised as shown in Fig. 11 it forces the jaws together as previously described. The slide plate may be raised by means of a hand lever 84 pivoted to guide 78 at 85 and having a slot 86 in which works a pin 87 upon said slide.

A gap intervenes between the clamping faces of the jaws at the upper ends thereof even when said jaws are closed, but this gap is filled by a vertically reciprocating clamping member 88 which descends to the position shown in Fig. 11 when the jaws are closed and ascends to the position shown in Fig. 12 when the jaws are open. The jaw 88 is formed on its rear face with a spline or dove-tailed key 89 which is guided in a vertical groove 90 formed in the face of the web. Its lower face 91 conforms to the cross-section of the mandrel and of the pipe section to be operated upon and the side edges 92, 93 thereof are inclined so that this portion of the clamp member is wedge-shaped to closely fit the gap between the upper ends of the swinging jaws when the latter are closed. The lower portion of the clamp member 88 just described is connected by a vertical web 95 extending between the upper ends of the pivoted jaws with a cross tree 96 which extends over the ends of the pivoted jaws. By an inspection of Figs. 11 and 12 it will be seen that the jaws 66, 67 are provided adjacent their pivots with cam faces 97, 98, respectively, which operate upon the rounded ends of the cross tree 96 when the jaws are opened to raise the sliding jaw 88 as shown in Fig. 12. When the swinging jaws are closed, however, the vertically sliding jaw descends and the swinging jaws bear thereon at 99, 100, respectively, to firmly press the sliding jaw against the pipe on the mandrel. The pipe lengths to be formed into elbows are thrust over or on to the mandrel to secure the location of the first crimp a proper distance from the end of the pipe lengths. The jaws are then closed and locked in closed position by raising the handle 84. The fixed clamp thereafter holds the pipe section firmly in position on the fixed mandrel, but the pressure is not such as to prevent the step by step movement of the pipe forward through the clamp, as herein-after described, without opening the latter which is maintained closed from the time the pipe section is inserted until the crimping thereof is completed.

The construction and operation of the

swinging clamp which cooperates with the swinging mandrel will now be described, reference being had particularly to Figs. 1, 3, 10, 13 and 14. The swinging jaws of the 5 swinging clamps are mounted upon a supporting plate 110 which is pivoted concentrically with the swinging mandrel by means of trunnions 111, 112 journaled in brackets 113, 114 which are bolted to the same cross 10 plate 65, heretofore described, which supports the fixed clamp. It will be noted that the trunnions mentioned are formed on or secured to rearwardly extending lugs 115, 116 on the plate 110 so that the plane of the 15 latter is somewhat in advance of the trunnions. Plate 110 is formed with an opening for the passage of the pipe section coaxial with the opening in the stationary supporting plate and with the mandrels. The jaws 20 118, 119 of the swinging clamps are hung on bolts 120, 121, respectively, cross each other at 122, embrace the swinging mandrel 54 and are provided with operating means, to be presently described, at their free ends. 25 In order that the jaws may cross each other at 122 and that at the same time the main bodies thereof may be opposite each other, the upper ends of the respective jaws are cut away as shown at 125, (see full lines in 30 Figs. 1 and 14 and dotted lines in Fig. 13), and suitable washers 126, 127 are applied to the bolts 120, 121 respectively, to secure the proper position of the jaws thereon. The inner or adjacent edges of the jaws are 35 shaped to conform to the pipe to be operated upon, and in the present instance are corrugated. They are cut away and overlap to some extent where they bear on top of the pipe as clearly shown in dotted and full lines in Figs. 13 and 14 and make contact with 40 the pipe from the point of overlap to some distance below the center thereof as shown in Fig. 13. I provide supplementary clamping jaws for engaging the lower portion of the pipe. These jaws or wings 130, 131 are 45 pivoted to a pin or bolt 132 which has a slight vertical movement in a slot 132^a in supporting plate 110, see dotted lines Fig. 14. The jaws or wings extend on opposite 50 sides of and beneath the swinging mandrel and the pipe thereon and when the jaws 118, 119 are opened fall outwardly by gravity, the pivot bolt 132 dropping to the bottom of the slot 132^a. When the jaws 118, 119 close 55 they engage the wings and raise and close the latter by engaging them with the cam surfaces 133, 134 which bear upon the outside edges of the respective supplemental swinging jaws. The supplemental jaws are 60 formed or provided with sections 135 and 136, respectively, of a guide for the seam γ of the pipe and, of course are correspondingly notched to allow for the feed. In order to limit the movement of the jaws they are 65 provided respectively with pins 137, 138 playing respectively in slots 139, 140 formed in the supporting plate 110.

At their respective free ends the jaws 118, 119 are provided with rollers 141, 142 journaled thereon for cooperation with the 70 means to be now described for both tilting the jaws and their supporting plate together and for opening and closing the jaws. This operating means is contained in a boxing 143 mounted on the frame beneath the jaws. 75 Within the boxing are a pair of independently actuated slides 144, 145 mounted one above the other and movable longitudinally of the machine. The lower slide 145 is provided with a transverse groove or channel 80 147 into which the rollers 141, 142 extend, the length of the channel being sufficient to provide ample movement for the opening of the jaws. When the slide is reciprocated the jaws and the supporting plate to which 85 they are attached are tilted on the trunnions 111, 112. The second or upper slide is provided with an obtuse V-shaped slot 148, the apex of the V being toward the rear, through the respective branches of which slot the 90 rollers 141, 142 extend. Obviously when the two slides move relatively to each other or when one moves while the other is stationary, the jaws are opened or closed.

The section of pipe being crimped to form 95 the elbow is fed forward step-by-step after its insertion in the machine by means of a collar 150 which slides upon the mandrel. The collar is recessed or its bore enlarged at 151 and receives a band 152 in the recess, 100 the interior of which is corrugated or otherwise formed to correspond to the exterior of the mandrel but is of sufficiently larger size to permit the insertion of the end of the 105 pipe section to be operated upon between 105 said band and the mandrel.

I will now describe the means for giving the parts thus far described their operative motions. Referring to Figs. 1, 2 and 4, it will be seen that the machine is provided at 110 its rear end with a transverse operating shaft 160, shown as driven by a belt pulley 161, and provided with a bevel pinion 162. Said pinion meshes with a bevel gear 163 keyed to a shaft 164 which is mounted co- 115 axially with the mandrel in brackets 165 and 32 on the main frame of the machine. Said shaft has keyed thereto the various cams for operating the moving members of the machine. At its rearmost end is the cam 168 for swinging the swinging mandrel. It is 120 grooved at 169 to receive the roller 170 of a longitudinally moving slide 171. To the upper end of the slide at 172 is secured a rod 173 which extends through an axial bore 174 in the shaft 164 and a similar bore 176 in the plunger 36. At its forward end said rod is provided with a flanged block 177 which 125 extends loosely through a vertical slot 178 in the swinging mandrel. The flanges 179, 130

180 of the block are obtuse angled in their respective adjacent faces, as best shown in Fig. 9, and engage the opposite faces of the swinging mandrel to permit a pivotal movement of the latter as the rod is reciprocated. Thus the mandrel may be swung from the normal position of Figs. 3, 9 and 16 to the inclined position of Figs. 4 and 15.

The cam cylinder 185 on said shaft controls both the opening and closing of the swinging clamp and the tilting thereof. As best seen in Figs. 2 and 4, it is provided with a cam groove 186 which receives a roller 187 carried by a slide bar 188 mounted for longitudinal reciprocation beneath said cam cylinder. As seen in Fig. 1, the forward end of said bar is dropped and receives the rear end of a rod 189, the forward end of which is connected to the slide 145 by which the swinging clamp and its supporting plate are controlled in their movements about the trunnions 111-112.

The other cam groove 190 in said cylinder receives the roller 191 on the slide bar 192, 25 the forward end of which is likewise dropped and connected by a rod 193 with the upper slide 144 which is formed with the V-slot, as above described, and controls the opening and closing of the jaws of the 30 swinging clamp. Immediately in advance of the cam cylinder 185 is a smaller cam cylinder 195 which operates to advance the collar 150 by which the pipe sections being converted into elbows are given their step by 35 step movement intermediate crimping operations. Cylinder 195 is formed with a cam groove 196 in which runs a roller 197 mounted on a stud on the reciprocating bar 198. The latter is guided at 199 in the bracket 32 and extends loosely through a 40 guide 200 upon the collar 150. The slide 198 is formed on its under edge with ratchet teeth or notches 201 which are engaged by a pawl 202 which is pivoted to said collar at 45 203, the pawl being held against the ratcheted face of the bar 198 by a spring 203^a. The collar is fed forward one notch or tooth with each reciprocation of said bar. 50 The rearward movement of the collar is prevented by a pawl 204 which is pivoted to the collar at 205 and pressed downwardly by the same spring 203^a which operates on pawl 202, and engages ratchet teeth 206 formed in the upper face of the mandrel.

55 formed in the upper face of the mandrel. A cam cylinder 207 of yet smaller diameter than cylinder 195 is carried on the front end of the shaft 164 and is journaled in the bracket 32, as best shown in Fig. 3. The cam cylinder or sleeve 207 controls the reciprocation of the plunger 36 by means of which the bulge forming knuckles are spread and retracted. For this purpose, the said sleeve is formed with a cam groove 208 in which runs a roller 209 mounted on the rear 60 under face of a slide block 210. Said block

is guided in the bracket 32 (see Figs. 3 and 5) and at the forward end of its under face is formed or provided with a lug or pin 211 which extends into a hole 212 formed in the rear end of said plunger. Obviously, as the shaft and the cam cylinder 207 rotate, the plunger is reciprocated operating the expanding knuckles as above described. 70

Automatic means is provided for stopping the machine and opening the fixed clamp when the elbow being formed is completed. For this purpose, a lever comprising the arms 215, 216 and shaft 217 is mounted on the side of the machine, as best seen in Fig. 2, the rear arm 215 controlling a clutch between shaft 160 and pulley 161. This clutch may be of any known or suitable construction adapted to be operated by a swinging arm, such as 215 and it is, therefore, not considered necessary to describe it. The other arm 216 of the lever extends to or past the front of the machine being guided and limited in its swinging movement by the guide bar 218. At its forward end as at 219, it extends beneath the hand lever 84 and so long as the arm 216 is elevated, in the position shown in Fig. 11, which is the position it occupies during the operation of the machine, it keeps the fixed clamp closed. When it drops, however, it permits the fixed clamp to open and likewise the dropping of the arm 216 of the lever accompanied as it is by the raising of the arm 215 throws out the clutch controlled by the latter thus bringing the machine to rest. Arm 216 is maintained in its upper or raised position by a latch 220 which slides crosswise of the machine, see Fig. 2. The inner end of the latch has a pin 221 which engages in a slot 222 in the end of the bell crank lever 223. The bell crank lever is pivoted at 224 and its shorter arm 225 extends into the path of a finger 226 depending from the collar 150. The contact of said arm 225 with the finger may be adjusted by means of the screw 227. When the last crimp has been formed in the particular elbow being made, the finger 226 engages the bell crank lever causing the latter to withdraw the latch 220 from beneath the arm 216 and the latter thereupon drops permitting the fixed clamp to open and opening the clutch by which the machine is driven.

The movement of the parts of the machine has been described in connection with their structure, but may be briefly summarized as follows: After each elbow is completed, the machine comes to rest with the bulge forming knuckles in the retracted position, the swinging mandrel co-axial with the fixed mandrel, the swinging clamp in vertical position and both clamps open, all as shown in Fig. 3. The pipe advancing collar is in its forward position having just tripped the stop mechanism of the machine. The pipe advancing collar, preferably, is first set back 120

to such a position that when the next pipe section to be operated upon is put on the fixed mandrel and properly engaged with the collar, it will be properly located with reference to the crimp forming means so that the first crimp will be properly placed. The location of the collar may be effected by pinching together the pawls 202, 204. A pipe length is then passed through both clamps and over the mandrels, with its seam underneath and guided in the seam guides 135, 136 and thrust rearwardly until in proper engagement with the advancing collar 150. By raising the lever arm 216, the fixed clamp is closed about the pipe on the fixed mandrel and the clutch shifted to set the machine in operation. The arrangement and relation of the cams is such that the slide 144 is first moved to close the jaws of the swinging clamp. The spreading of the crimp forming knuckles then takes place, due to the forward movement of the plunger 36, after which the knuckles are immediately withdrawn by the action of the cam. The swinging mandrel and swinging clamp are then swung rearwardly together by the operating means above described to fold the previously formed bulge rearwardly, as seen in Fig. 15. The slide 144 next moves rearwardly to release the jaws of the swinging clamp which, together with the swinging mandrel is moved to the upright co-axial position, shown in Fig. 3. The pipe section is then moved forward through the fixed clamp and over the fixed mandrel to the position shown in Fig. 16 in which the just formed crimp is within the plane of the swinging clamp. The jaws of the latter then close upon the folded metal of the crimp and press it flat. This completes the cycle of operation for the formation of the first crimp and the further operation of the machine again spreads the bulge forming knuckles and the other steps of the previously described operation are repeated. After the predetermined number of crimps have been formed in the pipe section, the advance of the pipe feeding collar operates the bell crank lever to release the clutch shifting lever and the machine returns to rest.

By reference to Figs. 11, 12, 15 and 16, it will be seen that the members of the fixed clamp are so shaped about their forward edges as at 231 as to form a tapering forwardly projecting nozzle, the opening of which is on an incline. It is also called to attention that the rear edge of the opening formed by the jaws of the swinging clamp is flared as at 232 so that when, upon the completion of the bulge, the swinging clamp is drawn rearwardly into the position shown in Fig. 15 the nozzle of the fixed clamp, along the upper portion of its edge, projects slightly within the rounded edge of the opening of the swinging clamp. As seen in Fig.

15, the mating of these parts is not such, however, as to squeeze the edge of the fold or crimp, but the latter remains slightly rounded. The joint action of the two clamps leaves the crimp standing out from the pipe at a slight angle as shown in Fig. 15, but when the crimp in this state is advanced and the jaws of the swinging clamp close thereon, the fold of the crimp is flattened down smoothly, as shown in Fig. 16. By thus avoiding crushing the metal flat at the line of fold during the operation of collapsing the bulge to form the crimp or tuck and thereafter flattening out the tuck or crimp by the action of the swinging clamp cooperating with the swinging mandrel, the tendency to crack the metal along the line or fold is greatly diminished, enabling the machine to be used for forming elbows of relatively brittle material, such as sheet zinc.

I claim:

1. In a machine of the class described, a mandrel, a pair of clamping jaws cooperating therewith, said jaws being pivoted at a distance from each other and crossing each other intermediate their respective pivots and the mandrel, and means operating on the free ends of the jaws for opening and closing them.

2. In a machine of the class described, a mandrel, a pair of clamping jaws cooperating therewith, the pivots of said jaws being spaced a substantial distance apart and said jaws crossing each other intermediate their respective pivots and the mandrel and each adapted to bear on the pipe on the mandrel for approximately a quarter of its circumference and means for clamping the pipe to the mandrel for approximately the other half of the circumference.

3. In a machine of the class described, a mandrel, a pair of clamping jaws cooperating therewith, the pivots of said jaws being spaced a substantial distance apart and said jaws crossing each other intermediate their respective pivots and the mandrel and each adapted to bear on the pipe on the mandrel for approximately a quarter of its circumference and means for clamping the pipe to the mandrel for approximately the other half of the circumference of the pipe, said means being operated by the opening and closing of said jaws.

4. In a device of the class described, a mandrel, a main pair of clamping jaws pivoted at a distance from each other and crossing each other intermediate their respective pivots and the mandrel and adapted to jointly operate on substantially a semi-circumference of a pipe on the mandrel, and a pair of supplemental pivoted jaws engaged by the main jaws and clamping the pipe substantially throughout the other portion of its circumference.

5. In a machine of the class described, a

- mandrel, a main pair of clamping jaws adapted to engage a pipe on the mandrel on the side thereof adjacent the pivots of said jaws, a pair of supplemental swinging jaws 5 adapted to engage the pipe on the other side thereof, said supplemental jaws engaged and operated by the main jaws and means for opening and closing the main jaws.
6. A machine as described in claim 5 in 10 which the means for opening and closing the main jaws engages the latter at their free ends.
7. In a machine of the class described, a mandrel, a pair of pivoted jaws cooperating 15 therewith and extending at their free ends on the opposite side of the mandrel from their pivots and a cam plate engaging the free ends of the jaws for opening and closing the latter.
- 20 8. In a machine of the class described, a mandrel, a pair of pivoted clamping jaws, a cam plate having a V-shaped slot through the respective arms of which the free ends of the jaws extend, and means for reciprocating the cam plate.
9. In a machine of the class described, a swinging mandrel, a pair of clamping jaws cooperating therewith, a pivoted supporting 30 plate on which said jaws are pivoted, the jaws being extended beyond the mandrel and means engaging the free ends of the jaws for swinging them and their supporting plate.
10. In a machine of the class described, a 35 swinging mandrel, a pair of clamping jaws cooperating therewith, a pivoted plate on which said supporting jaws are pivoted, a plate having a cam slot through which said jaws extend, means for reciprocating said cam plate, a second slide plate into which 40 said jaws extend and means for reciprocating said slide plate to swing the jaws and their support.
11. In a machine of the class described, a swinging mandrel, a supporting plate pivoted to swing with said mandrel, a pair of clamping jaws pivoted to said plate and cooperating with the mandrel, a pair of independently operated slide plates both engaging the jaws, one of said slide plates having a cam slot for opening and closing the jaws and the other slide plate having a transverse groove into which said jaws extend, and mechanism for operating the second said plate to swing the jaws and their support. 55
12. In a machine for forming pipe elbows from sheet metal pipe, a fixed mandrel adapted to receive a length of pipe from which an elbow is to be formed; a clamp surrounding the mandrel and having a lip extending partially around the inner periphery of the clamp, said lip having a narrow rounded edge, a second mandrel normally concentric with the fixed mandrel and adapted to swing to an inclined position, a clamp 60 surrounding the second mandrel and clamp, the second said clamp being rounded opposite the narrow lip on the first mentioned clamp so as to engage the rounded edge only of the latter, means for forming a bulge in 70 the pipe intermediate said mandrels and clamps when the latter are in normal position and means for swinging the last mentioned mandrel and clamp toward the first mentioned mandrel and clamp to collapse a 75 previously formed bulge in the pipe.

FRIEDERICH BRUNE.
